UNITED STATES PATENT OFFICE

EDWARD ENGEL, OF BLOOMINGTON, ILLINOIS, ASSIGNOR TO MULLINS MANUFACTURING CORPORATION, OF SALEM, OHIO, A CORPORATION OF NEW YORK

WRINGER

Application filed February 6, 1931. Serial No. 513,838.

The object of my invention is to produce a clothes wringer structure of the type wherein the upper roll of the roller pair may be associated with and dissociated from the lower roll by a lateral swinging movement of a supplemental upper frame bar which carries a spring abutted upper roll and forms a finish for the complete wringer, the construction being such that dissociation of the rolls, in case of accident, may be accomplished very quickly by the exertion of a comparatively small force transversely of the roll plane in a direction either from or toward the operator from either side of the wringer.

The accompanying drawings illustrate various forms of my improved structure.

Fig. 1 is a vertical axial section of one embodiment of my invention;

Fig. 2 a transverse vertical section on line 2-2 of Fig. 1, through the interlocking means between the base frame and the upper roll-carrying frame;

Fig. 3 a section similar to Fig. 2 with the upper roll frame swung to one side;

Fig. 4 a fragmentary horizontal section above the upper roll;

Fig. 5 a fragmentary detail of the fulcrum of the upper frame;

Fig. 6 a vertical axial section of another embodiment of my invention;

Fig. 7 a transverse vertical section of the form shown in Fig. 6;

Fig. 8 a view similar to Fig. 7 with the upper roll-carrying frame swung to intermediate position;

Fig. 9 a fragmentary horizontal section above the shaft of the upper roll as shown in Fig. 6;

Fig. 10 a fragmentary section through the latching means;

Fig. 11 a modified cam plate;

Fig. 12 a vertical axial section of another embodiment of my invention;

Fig. 13 a transverse section on line 8-8 of Fig. 7 with the upper roll frame in operative position; and

Fig. 14 a view similar to Fig. 8 with the upper roll-carrying frame swung to release position.

In the several figures 10 indicates a base,

conveniently formed of sheet metal if desired, having a trough-like middle portion 11 within which the lower roll 12 is situated. At each end the base is provided with an end plate 13 medially vertically slotted at 14 to permit the shaft 15 of the lower roll to descend to a proper position. Outside of each end plate 13 is a boxing 16 open at its top and adapted to receive a bearing block 17 for the lower shaft, the outer plate of one of said boxings being perforated at 18 to permit the projection of one end of shaft 15 for driving association with one end of the lower roll shaft.

Thus far the structures in the three forms shown in the drawings are substantially identical, differing perhaps in minor dimensions.

Referring now to Figs. 1 to 3. Vertically removably mounted in each boxing 16 is an anchor fitting 19 having depending legs 19' and an intermediate arc-shaped portion 20, the legs fitting within boxing 16 and held in place in any suitable manner such as by readily removable screws 21. Rising vertically from the middle of the arc 20 is an anchor finger 22 carrying at its upper end, on its opposite sides, anchor rollers 23 journaled on an axis parallel with the axis of the lower roll 12.

The upper roll 25 is carried by a swinging supplemental frame comprising a main bar 26 having depending legs 27, 27', each of which is vertically pocketed, as indicated at 28, to receive the shaft 25' of the upper roll and permit vertical movement thereof and to receive the upper roll bearing blocks 29, 29', which may be conveniently half blocks, and the pressure springs 30. The bearing blocks 29, pressure springs 30 and upper roll shaft 25' are limited in downward movement by couplings 31, 31', each of which is removably held in the swinging supplemental frame by any suitable means such as screws 32. Each coupling 31 is provided with two depending plates 33, 33', separated axially of the upper roll by an amount slightly greater than the total axial dimension of the anchor elements 22-23, and each plate 33 is provided at its lower edge with an inwardly-pro-

jecting cam flange 34 so arranged as to be forcible beneath one of the rollers 23.

The swinging supplemental frame may, in the main, be conveniently formed of sheet metal and, to give a finished appearance and hide the coupling between the base and supplemental frame, the end elements of the supplemental frame may be provided with depending lips 35 and the boxings 16 may have arc-shaped lips 36.

In order to form a definite fulcrum for the swinging supplemental frame, irrespective of the position of the upper roll in said frame, each coupling 31, on its inner face adjacent to the end of the upper roll, is provided with a semi-cylindrical flange 31', the outer diameter of which is substantially equal to the width of slot 14.

In this construction the swinging frame is tilted to an angle of about forty-five degrees and the upper roll is lowered down toward the lower roll with flanges 31' in slots 14 until the lower ends of the tilted cam flanges 34 are in a position to pass under the anchor 20 rollers 23. Thereupon the supplemental upper frame, fulcruming upon flanges 31' in slots 14, may be swung to a medial vertical position, thus forcing the cam flanges 34 under the rollers 23, thereby forcing the upper 25 roll down firmly upon the lower roll and compressing the springs 30 to the desired extent, the parts being then in the position shown in Fig. 1, in which position the supplemental frame, being firmly anchored to the base, is in position to afford a proper abutment to the springs 30 to coact with the upper roll when material is forced between the upper and lower rolls.

In case of accident the upper roll may be 40 immediately released from the lower roll by striking the upper bar 26 in a direction at right angles to the roll plane and swinging it to the position shown in Fig. 3.

In order to insure holding of the supplemental frame in its medial position against anything but intentional displacement, the flanges 34 may, at their middles, be provided with a slight depression 34' to receive the rollers 23, these depressions not being sufficient to add too greatly to resistance of the anchorage to dissociation by transverse force applied to the upper bar 26.

Referring now to Figs. 6 to 10. As in the form shown in Figs. 1 to 5 the supplemental 55 swinging frame comprises the upper bar 26, depending legs 27', upper roll 25, upper roll bearing blocks 29 and springs 30, separation of the upper roll from legs 27' being normally prevented by removable cross pins 40.

Spaced from the outer face of each leg 27' is a plate 41 which, near its lower edge, is connected to the adjacent leg 27' by two laterally-spaced pins 42, 42, the axes of which are parallel with the roll axes.

Rising from each boxing 16, in this form,

is a vertical cam plate 43 provided at its upper end with an inverted Y cam slot comprising the stem portion 44, open at its upper end, and the connected depending arms 45, 45, adapted to receive the cam pins 42, 42.

The Y-shaped cam slot may, it will be readily understood, be of various shapes, the construction shown in Figs. 7 and 8 being probably preferable for the reason that these cam slots at the middles of the branches 45 are provided with slight depressions 45' to afford a slight anchorage for the pins 42 against accidental swinging displacement of the supplemental frame from its normal medial operating position.

A cam slot of the form shown in Fig. 11 will be satisfactory but perhaps not quite so stable a structure as the cam slot construction shown in Figs. 7 and 8.

In this construction the parts are assembled by tilting the supplemental frame to a position in the neighborhood of ninety degrees from the vertical and entering the pins 42 in the stems 44 of the Y cam slots, whereupon each lowermost pin will move laterally into one arm of the Y and the upper pin may then be swung downwardly into the other arm of the Y until the supplemental frame is brought to a medial vertical position, at which time the upper roll is forced 95 down upon the lower roll. In the form shown in Figs. 7 and 8, when the swinging supplemental frame has been brought to medial position, the pins 42, 42 will lie in the shallow notches 45' in the arms of the Y cam 100 slots, thereby affording a stable anchorage for the supplemental frame which, however, may be readily displaced, to relieve the upper roll from pressure relationship with the lower roll, by displacement of the upper bar of 105 the supplemental frame to one side or the other of its medial position.

Turning now to Figs. 12 to 14. Each boxing 16 is flanked by an upwardly-extending anchor plate 50 provided at its upper end with an inturned flange 51 conveniently stiffened by a down-turned edge 52, each flange being preferably provided medially with a depression 53 in its under face. In this construction each depending leg 27' of the swinging supplemental frame is provided on its outer face with a plate 54 into which is detachably secured a trunnion pin 55 passed into said plate through a slot 56 in plate 50. Each plate 54, at its upper end, is provided with a roller 57 adapted to take under the adjacent flange 51.

In this construction, when the swinging frame is swung to one side or the other as indicated in Fig. 9, there is no pressure relationship between the upper and lower rolls.

Pressure relationship is established by swinging the supplemental frame to its medial vertical position, thus bringing rollers 130

57 under flanges 51, the swinging frame fulcruming upon pins 55 in slots 56.

In the construction shown in Figs 12 to 14 the swinging supplemental frame is not normally separable from the base, as in the constructions shown in Figs. 1 to 10 inclusive, but separation may be readily obtained when desired, as for instance for renewal of an upper roll, by removal of pins 55, whereupon 10 the supplemental frame may be readily withdrawn transversely from the position shown in Fig. 14. Pins 55 may pass through plates 54 and into angle pieces 60 which normally serve to limit vertical movement of the upper 15 roll shaft bearing block.

It will be readily understood that any suitable supplemental drain board construction may be associated with the trough of the base, but this detail forms no part of my 20 present invention and therefore is not indicated in the drawings.

It will also be understood that, in any of the forms a single bar spring or leaf spring may be substituted for the coiled springs shown, 25 without departing from my invention.

I claim as my invention:

1. A wringer comprising a base, a lower roll journaled therein, a supplemental swinging frame comprising a top bar and depending 30 legs, an upper roll rotatably and slidably supported in said legs, and vertically and horizontally interlocking elements, some carried by the base and others by the supplemental frame for interlocking the supplemental frame with the base by a swinging movement of the supplemental frame to a medial vertical position.

2. A wringer comprising a base, a lower roll journaled therein, a supplemental swinging frame comprising a top bar and depending legs, an upper roll rotatably and slidably supported in said legs, and vertically and horizontally interlocking elements, some carried by the base and others by the supplemental frame for interlocking the supplemental frame with the base by a swinging movement of the supplemental frame to a medial vertical position from either side of said medial position.

50 3. A wringer comprising a base, a lower roll journaled in said base, vertically-slotted end plates carried by said base, a swinging supplemental frame comprising a top bar and depending legs, an upper roll rotatably mounted in said legs, means rigid with said frame and forming a fulcrum for said frame on said base, anchor means carried by the base adjacent each end plate, and anchor flanges carried by the supplemental frame 55 and arranged to be projected under the anchor elements of the base by swinging movement of the supplemental frame to a medial vertical position.

60 4. A wringer comprising a base, a lower roll journaled in said base, vertically-slotted

end plates carried by said base, a swinging supplemental frame comprising a top bar and depending legs, an upper roll rotatably mounted in said legs, portions carried by said legs for rotative and sliding reception 70 in the slots of said end plates, anchor means carried by the base adjacent each end plate, and anchor flanges carried by the supplemental frame and arranged to be projected under the anchor elements of the base by 75 swinging movement of the supplemental frame to a medial vertical position.

5. A wringer comprising a base, a lower roll journaled in said base, vertically-slotted end plates carried by said base, a swinging supplemental frame comprising a top bar and depending legs, an upper roll rotatably mounted in said legs, resilient means engaging 80 said frame and biasing said roll toward movement in one direction with respect thereto, anchor means carried by the base adjacent each end plate, and anchor elements carried by the supplemental frame and arranged to be projected under the anchor elements of the base by 85 swinging movement of the supplemental frame to a medial vertical position.

6. A wringer comprising a base, a lower roll journaled in said base, vertically-slotted end plates carried by said base, a swinging supplemental frame comprising a top bar and depending legs, an upper roll rotatably mounted in said legs, portions carried by said legs for rotative and sliding reception in the 90 slots of said end plates, anchor means carried by the base adjacent each end plate, and anchor elements carried by the supplemental frame and arranged to be projected under the anchor elements of the base by 95 swinging movement of the supplemental frame to a medial vertical position from either side of said medial position.

7. A wringer comprising a base, a lower roll journaled therein, upwardly projecting plates at each end of said base, each of said plates having, in its upper end, an inverted Y slot, a swinging supplemental frame comprising a top bar and depending legs, and a pair of laterally-spaced cam pins carried by each leg and adapted to be projected into the Y 100 cam slots by a swinging movement of the supplemental frame.

8. A wringer comprising a base, a lower roll journaled therein, upwardly projecting plates at each end of said base, each of said plates having, in its upper end, an inverted Y slot, a swinging supplemental frame comprising a top bar and depending legs, and a pair of laterally-spaced cam pins carried by each leg and adapted to be projected into the Y 105 cam slots by a swinging movement of the supplemental frame in either direction to a medial vertical position, and an upper roll rotatably mounted in said legs.

9. A wringer comprising a base, a lower 110

- roll journaled therein, an upwardly-projecting anchor plate at each end of the base provided at its upper end with a lateral cam flange, a swinging supplemental frame comprising a top bar and depending legs, an upper roll rotatably mounted in said legs, a trunnion pin rotatably and vertically slidably mounted in a slot in the adjacent plate of the base, and an element carried by the swinging frame adjacent each end and positioned for projection beneath the adjacent cam flange, in either direction, toward a medial vertical position.
10. A wringer comprising a base, a lower roll journaled therein, an upwardly-projecting anchor plate at each end of the base provided at its upper end with a lateral cam flange, a swinging supplemental frame comprising a top bar and depending legs, an upper roll rotatably mounted in said legs, a trunnion pin rotatably and vertically slidably mounted in a slot in the adjacent plate of the base, and an element carried by the swinging frame adjacent each end and positioned for projection beneath the adjacent cam flange, in either direction, toward a medial vertical position.
11. A wringer comprising a base, a lower roll journaled therein, an upwardly-projecting anchor plate at each end of the base provided at its upper end with a lateral cam flange, a swinging supplemental frame comprising a top bar and depending legs, an upper roll rotatably mounted in said legs, a trunnion pin rotatably and vertically slidably mounted in a slot in the adjacent plate of the base, and an element carried by the swinging frame adjacent each end and positioned for projection beneath the adjacent cam flange toward a medial vertical position.
12. A wringer comprising a base, a lower roll journaled therein, an upwardly-projecting anchor plate at each end of the base provided at its upper end with a lateral cam flange, a swinging supplemental frame comprising a top bar and depending legs, an upper roll rotatably mounted in said legs, a trunnion pin rotatably and vertically slidably mounted in a slot in the adjacent plate of the base, and an element carried by the swinging frame adjacent each end and positioned for projection beneath the adjacent cam flange by a swinging movement toward a medial vertical position.
13. In witness whereof, I have hereunto set my hand at Indianapolis, Indiana, this 21 day of January, A. D. one thousand nine hundred and thirty-one.

EDWARD ENGEL.
